FIG. 1 is a perspective view of a tire embodying my new design, it being understood that the full line portion is repeated throughout the circumference of the tire, shown by means of broken lines;

FIG. 2 is an enlarged fragmentary elevational view of the full line sidewall portion shown in FIG. 1;

FIG. 3 is an enlarged fragmentary plan view of the full line portion shown in FIG. 1;

FIG. 4 is a sectional view taken substantially on the plane indicated by line 4-4 of FIG. 3, but on a reduced scale;

FIG. 5 is an enlarged detailed sectional view taken substantially on the plane indicated by line 5-5 of FIG. 3;

FIG. 6 is an enlarged detailed sectional view taken substantially on the plane indicated by line 6-6 of FIG. 3;

FIG. 7 is an enlarged detailed sectional view taken substantially on the plane indicated by line 7-7 of FIG. 3;

FIG. 8 is an enlarged detailed sectional view taken substantially on the plane indicated by line 8-8 of FIG. 4; and

FIG. 9 is an enlarged detailed sectional view taken substantially on the plane indicated by line 9-9 of FIG. 4.

The dominant features of my design reside in those portions shown in full lines in the drawing.

I claim:

The ornamental design for a tire, substantially as shown and described.
